FRANCES E. ISHAM, OF HARTFORD, CONNECTICUT, ADMINISTRATRIX OF
THE ESTATE OF HENRY ISHAM, DECEASED.

Letters Patent No. 98,972, dated January 18, 1870.

IMPROVEMENT IN PERMUTATION-LOCKS.

The Schedule referred to in these Letters Patent and making part of the same.

To all whom it may concern:

Be it known that HENRY ISHAM, deceased, of New Britain, in the county of Hartford, and State of Connecticut, did invent certain new and useful Improvements in Locks for Banks and Safes; and that the following is a full, clear, and exact description of the same, reference being had to the accompanying drawings, and the letters of reference marked thereon.

This invention relates to that class of locks in which each one of a series of tumblers is separately set in a given position by a key, or otherwise, and in which all the tumblers are turned from the key-shaft, by said key-shaft moving the first tumbler, said first tumbler moving the second tumbler, and so on through the pack; and has for its main object a novel method of construction, by means of which, picking, by the systems now known and practised, is effectually prevented.

It is not necessary to fully explain here the systems and processes by which locks of the character or class to which this invention relates have been picked; but it may be remarked, that one of the chief points in such systems and processes has been the exact knowledge of the different tumblers, and their positions, and of true and false notches, acquired by the picker by forcing the stump of the bolt back against the tumblers, and noting the index, indicating the degree of resistance offered, of an instrument used by the picker to designate, by the different degrees of pressure, the positions of the tumblers.

By means of this invention, any indication, by any instrument, of the positions of the tumblers is avoided; and

This invention consists in actuating the latch, by means of a travelling spring or weight, moving back and forth over the axis of motion of said gate, and connected to the sliding bolt, as will be presently more fully explained.

To enable those skilled in the art to make and use the improved lock, made the subject of this application, it will now be more fully described by reference to the accompanying drawings, in which—

Figure 1 is a back view of the lock.

Figure 2 is a cross-section at x x , fig. 1.

Figure 3 is a sectional elevation at y y , fig. 2, showing the bolt drawn in, and

Figure 4 is a similar view with bolt out.

Figure 5 is a detail face view of the latch, and

Figure 6 is a bottom view of same.

Figure 7 is a face view of one of the tumblers detached, and

Figure 8 is a section of same at x x .

Figure 9 is a side view of bolt detached.

Figure 10 is a side view of one of the plates arranged between the tumblers;

Figure 11 is an edge view of the same; and

Figure 12 is a view of the key, used to set the tumbler-rims on their centres in changing the combination of the lock.

In the several figures, the same part will be found designated by the same letter of reference.

A is the key-shaft, and B, the knob or handle, by means of which it is turned. This key-shaft, as usual, extends into the case E of the lock, and is provided with two circular disks, one of which, i , has teeth cut in its periphery, and forms a gear or spur-pinion, and the other, k , is left plain, as seen at fig. 2.

The key-shaft A is capable of both a rotary and limited longitudinal motion in its bearings. When pushed or moved longitudinally inward, its rotation will affect only the tumblers c d e of the lock, for the purpose of setting them, as will be presently explained, and when pulled outward, its rotation will affect only the bolt H, which is then driven, through the medium of its rack l and the pinion i of said key-shaft A a .

The bolt H is arranged to move in guides or bearings formed in the rim E, and at J, in about the usual manner, and it is slotted out at I, to permit it to straddle and work freely around the stud or shaft p of the latch G, which extends outward from the inner face of frame E, as clearly shown.

The bolt H carries a stump or projecting lug, w , which comes against the end of gate G, as and for purposes to be presently explained, and has attached to it a spring-stand or holder, x , from which projects a spring, t , designed to actuate the gate G at the proper times, during the sliding motions of the bolt, and throw it into and draw it out of the gates or slots r of the tumblers c d e .

In the plain portion m of the bolt H, at the lower edge, are cut two segmentary-shaped cavities or depressions, (see fig 9,) into one of which the disk k is moved, when the bolt is shot out for the purpose, holding it out, and into the other of which, it is moved when the bolt is drawn in, to hold it in.

The tumblers proper, alluded to as c d e , are each composed of two pieces, viz, rim-portions c d e , and centres f g h . The centres are simple disks, which are hung to turn freely in either direction on the smaller portion a of the key-shaft, and which have their peripheries grooved out, as clearly seen at figs. 2 and 8, and the rims c d e are simple, flat, split rings, which are sprung over, and adapted to fit into the grooved peripheries of the said centres.

In each of the rims, a gate or opening is cut, as seen at r , fig. 7, for the accommodation of a key or flattened rod, such as shown at 2, fig. 12, which is employed to spring open the rim, so that it may be turned on its centre for adjustment, as will be presently explained more fully.

The tumblers are arranged with plates s s between

them, to keep them apart on the key-shaft the proper distance, and they are held on by a confining-plate, *j*, which is bolted to proper seats formed in the body of the lock, as clearly seen, and which has a hole cut in it at *y*, to permit the introduction to the split rims *c d e*, of the key *z*². The back plate of the lock also has a hole through it, at *y'*, for the same purpose.

The latch *G* is slotted out, as shown at fig. 6, and has arranged within it, and so as to turn on its stud *p*, a catch-bar, *o*. This bar *o* is so made and arranged that it will receive and act as an abutment to the stump *w*, while the end *v* of the gate *G* is free to vibrate or move up and down around the axis-stud *p*. The extent of play, however, permitted to the bar *o* is so little that it will rise with the end of latch *G*, at the proper time to allow the passage back of the stump *w*, when the bolt is drawn back to unlock.

On the centre *f*, of tumbler *c*, is a projecting pin, *7*, against which the lug *6* on shaft *a* strikes, when said shaft is pushed in to operate the tumblers.

On centre *g* are two lugs *4 4*, between which the pin or arm *5* of shaft *a* catches, and on centre *n* is a lug, *3*, which comes in contact with the pins *1 2*, projecting from the toothed disk *i*, and by means of these said pins and projections on the shaft *a*, and the centres *f g h*, the tumblers are rotated and set by the key-shaft, so that their gates or slots *r* all come in line, to permit the dropping into them of the latch *G*. This adjustment of the tumblers is, of course, affected by noticing the index at *b* and *c*, and forming the given combination in about the usual manner.

It will be observed that there is a space left between the disk *k* and the pinion *i*, equal in width to the thickness of the plain or untoothed portion *m* (see fig. 2) of the bolt, the object and effect of which peculiarity of construction are the passage of the portion *m* between *i* and *k*, the moment the bolt begins to move, and the prevention of any end play to shaft *a a*, and consequently the avoidance of any disturbance of the "set" tumblers, and the retention of the rack *l* and pinion *i* in perfect gear.

It will be seen, that when the bolt *H* is out, as seen at fig. 4, (and the parts in the relative positions therein shown,) if it be forced backward, (or into the lock partially,) the stump *w* will come against the shoulder of catch or stop-bar *o*, and that this bar *o*, taking

its abutment against the stud *p*, on which it is hung, and being free to move slightly independently of catch *G*, the latter will not be pressed at all upon the tumblers, or, in other words, there will be no different effect on the bolt, or any pressure-indicator attached to it, by reason of the latch *G* resting on one or more or different-sized tumblers, because the dead-lock will be between the fixed stud *p* and the bolt *H*, through the medium of the bar *o*, and the latch *G* will always play independently of these parts, so that it cannot be made a medium for testing pressure or discovering the position of the tumblers.

The manipulation of the tumblers, to set them by the key-shaft, is made according to the known combination of movements from the index, with the key-shaft pushed in, in the usual manner, and whenever it is desired to change the operation or combination, any one or more of the tumbler-rims *c d e* may be turned on its centre, so as to change the relative position of its gate *r* to the lugs *1 2*, and *c*, and pins on the centres and key-shaft, by means of the key *z*², inserted from the back of the lock, to spring open and hold the rim, while its centre is turned around within it by means of the key-shaft.

It is known that a latch hung on a fixed centre, and actuated by the bolt, has been before combined with a bolt and a series of tumblers. This combination, therefore, is not claimed, except as below stated; but

What is claimed as new, and desired to be secured by Letters Patent, is—

1. The dog, or latch, when operated by a shifting pressure, proceeding from the bolt, and operating alternately on different sides of the fulcrum of the latch, substantially as set forth.

2. The employment, in combination with the bolt *H* and a series of tumblers, of a latch, *G*, or its equivalent, hung on a fixed centre, and actuated from the bolt, in the manner above claimed.

In testimony whereof, I have hereunto set my hand and seal, this 23d day of November, 1869.

FRANCES E. ISHAM, [L. S.]
Adm. of Estate of Henry Isham, Deceased.
